UNITED STATES PATENT OFFICE.

JENS N. JACOBSEN, OF EUREKA, CALIFORNIA, ASSIGNOR TO INTERNATIONAL WRAPPING MACHINE COMPANY, OF EUREKA, CALIFORNIA, A CORPORATION OF CALIFORNIA.

BUTTER-MOLD.

No. 903,982.

Specification of Letters Patent.

Patented Nov. 17, 1908.

Application filed April 23, 1908. Serial No. 428,815.

To all whom it may concern:

Be it known that I, JENS N. JACOBSEN, a citizen of Germany, residing at Eureka, in the county of Humboldt and State of California, have invented new and useful Improvements in Butter-Molds, of which the following is a specification.

The object of the present invention is to provide a butter mold of such construction as to permit the mold to be wheeled up to the churn and the butter molded directly therefrom; and in which a large quantity of butter can be stored in a comparatively small space, while at the same time there is ample air space around the butter to permit it to cool.

In the accompanying drawing, Figure 1 is a side elevation, broken away in parts, of my improved butter mold; Fig. 2 is a plan view thereof; Fig. 3 is a transverse section thereof; Fig. 4 is an enlarged broken transverse vertical section through one of the devices for raising and lowering the molds.

Referring to the drawing, 1 indicates a truck frame, comprising outer longitudinal or side beams 2, inner longitudinal beams 3, transverse spacing bars 4, transverse tie rods 5, connecting the side beams, and firmly clamping the spacing bars between the longitudinal beams, end beams 6 resting on rabbed ends 7 of the side beams 2 and in recesses 8 in the ends of the inner longitudinal beams 3, vertical bolts 9 through the end beams and longitudinal beams, corner posts 10 resting upon the ends of the end beams, upper longitudinal beams 11, secured to the tops of said posts, transverse bars 12 secured by bolts 13 to the under sides of the ends of said beams 11, racks 14 secured to the inner sides of said beams 11, and guide bars 15 secured to the inner sides of said racks.

Supported in each end beam 6, near each end thereof, is a shaft bearing 16, into the lower end of which is screwed a screw 17, upon the top of which screw is supported a wearing disk 18, convex on both sides, upon which disk can rest, in said bearing 16, the lower end of a screw 19. To said lower end of the screw 19, above the step bearing 16 formed by the disk 18 and bearing 16, there is secured a bevel gear 20, which gear meshes with two bevel gears. On the one side, namely, in the direction towards the near outer side of the truck, it meshes with a

bevel gear 21 upon a short transverse operating shaft 22 rotatable in a bearing 23 let into the corresponding corner post 10, extending to the outside of said posts, said shaft 22 being there adapted to support a crank handle 24 by which it can be turned. On its other, or inner, side, said lower bevel gear 20 meshes with a bevel gear 25, the four gears 25, at the two sides of the truck, being secured, in pairs, to transverse shafts 26 rotating in bearings 27 on the tops of the inner longitudinal beams 3. The two transverse shafts 26, at the front and rear ends of the apparatus, are connected to rotate in unison by means of a sprocket chain 28 carried by sprocket wheels 29 on said shaft 26. It will readily be seen that by means of this construction, a rotary motion imparted to any one of the four short shafts 22, by a crank handle 24 on its end, will rotate all of said screws 19 in unison. All of said screws 19 screw through internally threaded sleeves 30, having flanges 31 by which they support transverse beams 32 of a mold frame, so that, by the rotation of said screws 19, said transverse beams 32 at the front and rear ends of the machine are raised or lowered in unison, or in a parallel movement, being maintained level in each vertical movement. Upon said transverse beams 32 rest longitudinal beams 34, maintained in place by means of dowel pins 35 entering sockets in said transverse beams 32. Upon said longitudinal beams 34 are supported a vertical series of butter molds 33, of which there are here shown three, although the number may be varied according to requirements.

All the butter molds are identical in construction, and each one rests in a uniform manner upon the one below it, and in the same manner in which the lowest butter mold rests upon the longitudinal beams 34, which is as follows:—The top of each side 36 of the butter mold is formed with a half-round longitudinal groove to receive a round bar 37 of cold rolled steel, extending from end to end of said beam. The slats 38, which form the removable bottom of the butter mold, have secured thereto depending brass pieces 39 having half-round sockets which engage the upper sides of the round steel bars 37 and thus slidably support the mold thereon.

The construction of the mold itself is, in

general, of the character common in the art, that is, it comprises, in addition to the slats 38, the sides 36, which have dowel pins 35 extending into the slats 38, and the usual 5 end pieces. The lower molds, however, differ from the topmost mold in having, in the tops of their sides, half-round grooves to receive the round cold rolled steel bars 37, these bars being each used to support the 10 mold immediately above by means of the brass sockets 39 depending from the slats of said latter mold. These slats 38, and the sockets secured thereto thus engaging said bars 37, serve to hold together the tops of 15 the sides of the mold below it. The sides of the topmost mold are held together by the usual tie-bars 42 hooked at the end to engage said sides.

In operation, the truck is moved up to the 20 churn, the first or lowest mold set up upon the truck, the butter molded therein from the churn, and the lowest mold then lowered by means of a crank handle 24. The second mold is then put together on the top of the 25 first mold, and the butter is molded therein in the same manner as before and said second mold is then also lowered. The third mold is then assembled and the butter molded therein and the tie-bars placed 30 across the top. The molds are then in use. It will be observed that by means of this construction there is an ample air space between the molds to allow the butter to cool. The truck can then be attached either to a 35 cutting machine or to a wrapping machine, and it is evident that the height of any mold can be accurately adjusted to any desired level to coöperate with such a machine. The butter can then be unloaded one mold 40 at a time, beginning with the uppermost mold. As each upper mold is emptied of the butter, it is removed, and the next lower mold is raised into position by means of the crank handles 24. This construction effects 45 a great saving of the space required for storing the butter in molds, as thereby three molds of butter can be stored on substantially the same floor space as was formerly required for one mold.

50 I claim:—

1. The combination of a mold support, a vertical series of molds on said support means for raising said support and series, each upper mold being movable longitudinally relatively to the one below it and the lowermost mold being movable longitudinally relatively to the support.

2. In combination with a suitable carriage, a butter mold, and means at each side of the 60 carriage, each of which is operatively connected to said butter mold to raise or lower the same relatively to said carriage, substantially as described.

3. In combination with a suitable carriage, 65 a butter mold, means located at the front

and at the rear end of the carriage for raising and lowering said mold relatively to said carriage, and mechanism for operating said means in unison, substantially as described.

4. In combination with a suitable carriage, 70 a rectangular butter mold over said carriage, and devices located adjacent to the four corners of the mold, for operating all four corners in unison, to raise or lower said mold, substantially as described. 75

5. In combination with a suitable carriage, transverse shafts upon said carriage, means for connecting said transverse shafts whereby they rotate in unison, bevel gears thereon, vertical screws adjacent to the ends of said 80 transverse shafts, bevel gears thereon meshing with the former bevel gears operating shafts, bevel gears thereon meshing with the bevel gears on the screws, a mold frame, threaded sleeves in said mold frame engaging 85 said screws, and molds carried by said mold frame, substantially as described.

6. In combination with a suitable carriage, transverse shafts upon said carriage, means for connecting said transverse shafts whereby they rotate in unison, bevel gears thereon, vertical screws adjacent to the ends of said 90 transverse shafts, bevel gears thereon meshing with the former gears, a step bearing for each screw, means for varying the height of 95 each step bearing, operating shafts, bevel gears thereon meshing with the bevel gears on the screws, a mold frame, threaded sleeves in said mold frame engaging said screws, and molds carried by said mold frame, substantially as described. 100

7. The combination of wheels, axles therefor, inner and outer longitudinal beams supported by means of said axles, and beams supported by said longitudinal beams, 105 corner posts upon said end beams, means for connecting the tops of the corner posts, a mold frame, and means supported by said corner posts for raising and lowering said mold frame, substantially as described. 110

8. The combination of wheels, axles therefor, inner and outer longitudinal beams supported by means of said axles, and beams supported by said longitudinal beams, corner posts upon said end beams, means for 115 connecting the tops of the corner posts, a mold frame, threaded sleeves secured to said mold frame, threaded shafts engaging said sleeves, step bearings for said shafts secured to said end beams, operating shafts operatively connected with said threaded shafts to turn the same and bearings for said operating shafts supported by said corner posts, substantially as described. 120

9. The combination of wheels, axles therefor, inner and outer longitudinal beams supported by means of said axles, and beams supported by said longitudinal beams, corner posts upon said end beams, means for connecting the tops of the corner posts, a 125 130

- 5 mold frame, threaded sleeves secured to said mold frame, threaded shafts engaging said sleeves, step bearings for said shafts secured to said end beams, operating shafts operatively connected with said threaded shafts to turn the same, and means for operatively connecting said threaded shafts whereby they rotate in unison, substantially as described.
- 10 10. The combination of slats composing the bottom of a mold, socket pieces secured to said slats, supports for said mold, and bars round at the top and resting upon said supports, said bars being movably engaged by said socket pieces, substantially as described.
- 15 11. The combination of a mold support, means for raising and lowering said support in a parallel movement, and a vertical series 20 of molds upon said support, each upper mold being movable longitudinally upon the one below it, and the lowermost mold being
- movable longitudinally upon the support, substantially as described.
12. The combination of a mold support, 25 means for raising and lowering said support in a parallel movement, and a vertical series of molds upon said support, each lower mold and the support having parallel longitudinal bars rounded at the top, the 30 bottom of each mold being formed of slats, each slat having socket pieces at its ends, said socket pieces being concaved on their under sides, and slidably supported upon the corresponding bar, substantially as de- 35 scribed.

In testimony whereof I have hereunto set my hand in the presence of two subscribing witnesses.
